INVENTOR.

Clay N. Dybvig
BY Francis D. Hardesty

ATTORNEY.

UNITED STATES PATENT OFFICE.

OLAF N. DYBVIG, OF DETROIT, MICHIGAN.

FURNACE.

Application filed July 6, 1926. Serial No. 120,627.

The present invention relates to household heating furnaces and more especially to furnaces of the hot air type.

Among the objects of the invention is to increase the efficiency of the heat exchange between the combustion chamber and gases and the air to be heated.

Another object is the provision of a cheaper and more efficient and more easily 10 constructed and installed radiating element for a furnace of this type.

Other objects will be readily seen by those skilled in the art upon reference to the following description and drawings, in 15 which:

Fig. 1 is a vertical section with parts in elevation of a furnace involving the invention;

Fig. 2 is a horizontal section through the 20 furnace on line 2—2 of Fig. 1;

Fig. 3 is a detail view partly in section and partly in elevation of one of the connecting members.

As indicated in the drawings, the furnace 25 consists of a central combustion chamber 10 preferably of sheet metal and closed at the top with a cap 11 which may be riveted or welded in place. This chamber 10 is mounted upon a base member 12 in a substantially air-tight manner, preferably by placing the lower edge of chamber 10 in a groove in the top of the base member 12.

In the drawings, the combustion chamber is shown as having therein an oil burner 15 built according to the description set forth in my application for Letters Patent of the United States, Serial Number 108,509, filed May 12, 1926, but it should be noted that the features of the present invention are not 40 limited to oil burning furnaces but may be utilized in furnaces adapted for the combustion of coal or other fuel.

Near the top of the chamber 10 there is a flue 16 leading therefrom to a ring-shaped 45 radiator 20, and directly opposite the connection between the flue and the radiator is a continuation 17 of the flue 16 leading to a stack 18. This flue 17 is preferably controlled by the damper 19.

The radiator 20 is of somewhat larger diameter than the chamber 10 and is located concentrically therewith near the top of the chamber. This radiator 20 is connected on the side opposite the flue 16 by means of a 55 connecting member 21, more specifically

hereinafter described, to a second radiator 22. The radiator 22 is of somewhat larger diameter than the radiator 20 and is located concentric with chamber 10 at a lower level than radiator 20. A third radiator 24 of 60 substantially the same size as radiator 20 is located below the radiator 22 and concentric with the chamber 10 and is connected to radiator 22 by means of a connecting member 23 which is similar to the connecting 65 member 21. The radiator 24 is connected through a third connecting member 25, similar to the other two, to a lower radiator 26 which is of substantially the same size as radiator 22. This lower radiator 26 is 70 connected through a flue 30 to the stack 18, as indicated, and the draft for the furnace is controlled by a damper 31 in the stack.

About the lower end of chamber 10 there is preferably a cylindrical sheet metal shield 75 35 spaced from the chamber and concentric therewith and with the radiator 26. The purpose of this shield 35 is to prevent the radiation of heat from the lower part of the combustion chamber to the radiator 26, as 80 will be more fully set out later.

The assembly of the chamber 10, base 12 and radiators 20, 22, 24, and 26 is enclosed within a suitable outer casing 40 having air inlets 41 and outlet conduits for heated air 85 42 leading to the parts of the building to be heated, and suitable means, not shown, will be provided for supplying air and controlling the draft to the combustion chamber.

The several radiators and connecting members are preferably formed of sheet metal and each radiator is preferably made in four parts. Two of these parts will be semi-circular channel-shaped members 95 curved inwardly and the other two parts will be semi-circular channel-shaped members curved outwardly and mating with the first two members to form substantially complete circular conduits. These mating members will be provided with flanges and the flanges crimped together to form a substantially air-tight joint. A conduit will be so formed as to be substantially oval in cross section, that is, one in which the vertical 100 axis will be quite substantially longer than the horizontal axis, as indicated in the drawings. A conduit formed in this shape conforms more nearly to the stream-line of the rising air in casing 40 and therefore permits 110

the air to contact with the outer surface of the radiator much more effectively than if the latter were circular in section.

The connecting members 21 will be formed of two halves in the same fashion as the radiator and may have the flue ends so arranged as either to enter the half radiators 20, 22, etc., or to have the ends of the radiators enter the connecting member. In the form shown in Fig. 3, the radiator ends pass over the ends of the connecting member.

It will be seen from Fig. 1 that the radiators are arranged in vertical series relation and staggered in effect so that they substantially fill the cross sectional area of the air passageway between chamber 10 and casing 40. Such an arrangement, together with the stream-line shape of the radiators, gives a very efficient heat transfer between the combustion gases passing through the radiators and the air passing over the outside.

By means of the dampers 19 and 31, the flow of combustion gases through the several radiators may be very easily and efficiently regulated so that the gases passing out of stack 18 may be cooled almost to ordinary atmospheric temperature. This ar-

rangement allows a very efficient combustion of the fuel used.

Having now described the invention and the preferred form of embodiment thereof, it is to be understood that the said invention is not to be limited to the specific details of construction herein shown but only by the scope of the claims which follow. 35

I claim:—

1. A heating furnace consisting of a combustion chamber, a casing enclosing said chamber and spaced therefrom, a vertical series of horizontally arranged sheet metal 40 radiating flues disposed in the said space in staggered relation, and a heat shield disposed between the lower part of the combustion chamber and the lowermost flue.

2. In a hot air heating furnace, a combustion chamber, a plurality of radiating flues connected thereto and arranged horizontally and in vertical series relation whereby the air to be heated and the combustion gases may be conducted in counter-current relation, and means for preventing re-heating of the coolest combustion gases by radiation from the combustion chamber. 45 50
